Inventor:

Robert Speidel.

UNITED STATES PATENT OFFICE.

ROBERT SPEIDEL, OF CALMBACH, GERMANY.

PACKAGE.

1,406,098.

Specification of Letters Patent.

Patented Feb. 7, 1922.

Application filed July 9, 1920. Serial No. 395,073.

To all whom it may concern:

Be it known that I, ROBERT SPEIDEL, a citizen of the German Empire, residing at Calmbach, Wurttemberg, Germany, have 5 invented certain new and useful Improvements in Packages, (for which I have filed applications in Germany, Oct. 19, 1917; Denmark, Aug. 2, 1918; Sweden, Dec. 19, 1919; Norway, Dec. 23, 1919; Austria, Dec. 17, 10 1919; Switzerland, Dec. 31, 1919,) of which the following is a specification.

My invention refers to packages and more especially to the packing-up of fish, meat and the like, its particular object being a 15 package allowing to safely forward such and other easily perishable goods packed in ice.

It is old to dispatch victuals in double walled containers which, however did not 20 answer their purpose to full satisfaction.

In those cases, where only smaller quantities of ice were used for keeping the victuals in fresh condition, the melting ice, provided that the distance was not too long, 25 could be kept back in the container by aid of suitable absorbing means. For long distance forwarding however the ice as well as the absorbing means had to be renewed in time, much trouble and costs being 30 caused thereby. Moreover the transport had to be interrupted in many cases. If greater quantities were employed, the victuals were spoiled in general owing to the lack of ventilation and to the fact of the melting ice 35 not being absorbed.

In the package according to the present invention, now, these drawbacks are successfully avoided. In the novel package substantially consisting of a double walled 40 container the lower parts of the vertical walls of the inner box, which are firmly secured to the bottom of the outer one, are provided with ledges carrying a removable frame serving as a bottom for the inner 45 box or container, the said frame being designed to form a hollow space serving to take up the insulating material as well as the water dripping off the melting ice and escaping through openings provided in the 50 said frame. Above the outer bottom as well as above the frame there is arranged a thin

layer of wood-wool which is designed to prevent the insulating material from falling out through the openings provided in the outer bottom and further to facilitate the escape 55 of the water.

In the drawings affixed to the specification and forming part thereof a package embodying my invention is illustrated by way of example. In the drawings: 60

Fig. 1 is a horizontal longitudinal section on the line *c-d*,

Fig. 2, a vertical cross section on the line *a-b*,

Fig. 3, a horizontal longitudinal section 65 on the line *o-p*,

Fig. 4 a vertical cross section on the line *m-n*.

Referring to the drawings, *a* is the outer container and *b* is the inner one; *d* are the 70 fish or the like packed in a well known manner in ice *e* and in wood-wool, straw or the like; *o* are the ledges, disposed near the lower parts of the side walls of the inner container and *x* is the frame removably disposed on said ledges and having openings *g* provided therein which allow melting water to drip through into the space *c*¹ serving to take up insulating material. 75

The frame *x* can easily be removed by aid 80 of folding rings *k*. Immediately above the openings *g* arranged in the frame *x* as well as in the outer bottom of the container, there is disposed a thin layer of wood-wool which is preferably covered with sawdust as 85 an insulating material. The thin layer of wood-wool or the like besides acting as an insulation also acts as a means for absorbing the water dripping off the melting ice.

Before filling afresh a packing of the 90 kind before said, the frame need merely be removed in order to replace the saw dust or the like, and if necessary also the layer of wood-wool by fresh material whereupon the frame is put in again and ice and victuals 95 can be packed thereon.

The insulating material filling the space *c* between the covers of the two containers need merely be taken out as the package is being emptied and can be used again. The 100 covers of both containers are preferably hinged thereto and the outer container is

preferably adapted to be locked in such a way as to avoid nailing the cover down on the box.

I claim:

- 5 In a device of the kind described in combination, an outer box, ledges on the bottom of said box in parallel with, but at a distance from the sidewalls thereof, a perforate plate loosely resting on said ledges,

a box open on one side resting in inverted position on the bottom of said outer box with its side walls in frictional contact with said ledges, and absorbent material intermediate said outer box and said inner box and said plate, respectively.

15

In testimony whereof I affix my signature.

ROBERT SPEIDEL.
